COOKING RANGE CONTROL PANEL

Richard E. Hitchcock, Birmingham, Mich., assignor to Detroit-Michigan Stove Company, Detroit, Mich., a corporation of Michigan

Application July 28, 1952, Serial No. 20,781

Term of patent 14 years

(Cl. D81—25)

To all whom it may concern:

Be it known that I, Richard E. Hitchcock, a citizen of the United States of America and a resident of the city of Birmingham, county of Oakland, and State of Michigan, have invented a new, original, and ornamental Design for a Cooking Range Control Panel, of which the following is a specification, reference being had therein to the accompanying drawing, forming a part thereof, wherein:

Figure 1 is a front elevational view of a cooking range control panel, showing my new design;

Figure 2 is a top plan view of the control panel; and

Figure 3 is a section on the line 3—3, Figure 1.

The control members in Figure 1 are lined for contrasting color.

I claim:

The ornamental design for a cooking range control panel, substantially as shown and described.

RICHARD E. HITCHCOCK.
